CLAIM

The ornamental design for the PCV adapter, as shown and described.

DESCRIPTION

FIG. 1 is a top perspective view of a PCV adapter in accordance with the present invention;

FIG. 2 is a bottom perspective view of the PCV adapter of FIG. 1;

FIG. 3 is a top plan view of the PCV adapter of FIG. 1;

FIG. 4 is a bottom plan view of the PCV adapter of FIG. 1; and,

FIG. 5 is a side elevation of the PCV adapter of FIG. 1; the other sides being identical.

The broken line showing of a PCV adapter is for the purpose of illustrating portions of the article and forms no part of the claimed design.

1 Claim, 3 Drawing Sheets(56)
